UNITED STATES PATENT OFFICE.

HARUICHI KOHIROGAWA, OF PORTLAND, OREGON.

NECKTIE-FORM.

1,322,581.

Specification of Letters Patent. Patented Nov. 25, 1919.

Application filed February 26, 1918. Serial No. 219,336.

To all whom it may concern:

Be it known that I, HARUICHI KOHIROGAWA, a subject of the Emperor of Japan, a resident of the United States, in the city of Portland, the county of Multnomah, and State of Oregon, have invented certain new and useful Improvements in Necktie-Forms, and do hereby declare that the following is a full, clear, and exact description of the same, reference being had to the accompanying drawing, forming part of the specification, and to the letters and numbers of reference marked thereon.

This invention relates more particularly to that class of neckties known as four-in-hand, and a means of attaching and removing them from the wearer without untying same.

The object of this invention is to provide a simple and rapid means of attaching a necktie to a collar and to render untying unnecessary, which fact it is intended shall increase the life of the fabric.

It is a further object of this invention to facilitate the adjustment of the tie, particularly in that style of collar known as double or lay-down collars where it is difficult to adjust the ordinary four-in-hand tie, as the neck-band of the tie is difficult of adjustment as it frequently sticks in the fold of the collar, whereas in my invention the band is put in place in the collar before the collar is put on, and when the collar is put on and fastened to the shirt the body of the tie hereinafter described is slipped in place and adjusted on the free ends of the neckband, without the necessity of moving the band in the collar. However, it is not my intention to limit my invention to the style of collar herein described, but it may be used on any ordinary "stand-up" or "wing" collar, in which case the tie is put on after the collar is fastened to the shirt.

Referring to the accompanying drawing, Figure 1 is a front and side elevation of my device; Fig. 2 shows the device having a neck band of a tie threaded through the eyes and clamp of the device; Fig. 3 shows a tie made up on a wire form; Fig. 4 shows a tie on a straight collar; Fig. 5 shows a tie attached to a double or lay-down collar; Fig. 6 is a side elevation showing a tie attached to a collar which is partly cut away; Fig. 7 is a rear elevation showing the relation between a necktie, the form and a band for securing same to a collar.

Like letters and numbers of reference in the several figures indicate the same or similar parts.

A¹ is a spring form for a tie in which the spring loop A² serves to guide the neck band as well as to furnish more spring to the form. On the free ends of form A¹ are thumb grips A³ whose function it is to receive pressure from the thumb and forefinger causing clamp A⁴ to open. Clamp A⁴ is produced by the two free ends of form A¹ being crossed and twisted at their point of contact for the purpose of securing the free ends of the neck band, which have previously been passed through spring loops A². B¹ is an ordinary four-in-hand necktie. B² is a separate neckband having two free ends.

The operation of my device is as follows: A neck band with two narrow ends is threaded through eyes A² and the clamp or opening A⁴ while enlarging it by applying pressure with the fingers at A³ in the direction of the arrows. It will be noticed that as long as the pressure is applied at A³ that the neck band ends can move easily through A⁴, but as soon as released the jaws clasp the strings firmly in any desired position.

A four-in-hand tie is now tied upon the form without having to pass around the wearer's neck. The neck band is now slipped into the collar and adjusted to a central position on the collar, which is afterward fastened on the shirt and the neck band string pulled while pressing thumb grips A³, which are released when the tie is in proper position when the tie will be securely held in place.

It will be observed that in adjusting the neck band to the collar the operation is performed before the collar is put on the shirt, which permits the band to slip easily through the collar folds, after which it is unnecessary to move the neck band through the collar folds, since the adjustment of the tie to the collar is accomplished by moving both ends of the neckband through the tie. Whereas in the existing method one end of the band is secured to the collar and the other end passes around the collar and back through the tie knot, it is apparent that no adjustment can be secured without sliding the neck band portion which is now securely held by the buttoned collar and requiring undue attention on the parts to effect the adjustment. Furthermore, when once tied on the form it is not necessary to unfasten

the tie, which is a further saving of time and wear on the tie material.

Having thus described my invention, what I claim as new and desire to secure by Letters Patent of the United States, is:

1. In a necktie form and securing device the combination of a neck band member with a necktie member constituting that style of tie known as the four-in-hand, and a tie knot 10 form and position retaining member constituting a spring wire form having an initial shape of an inverted U with a coiled spring formed at each bend of the closed portion of the U and having a bend near 15 each of the open ends of said U shaped member of such shape that when the legs of the said U shaped member are sprung together they can be crossed so as to form a loop, and the extreme ends of the open por-

tion of said U shaped part are formed into 20 thumb grip members for the purpose set forth.

2. In a necktie form and securing device consisting of a form means constituting a wire frame member having the shape of an inverted U the lower ends of which are crossed to form a clamping loop for a neck band having free ends, and the extreme ends of the wire are formed into thumb grips for actuating the clamping means while the 25 closed portion of the frame has a coil spring loop formed at each bend for the purpose of increasing the spring effect of the clamp, together with a neck band having free ends 30 threaded through the coiled spring members and clamping means.

HARUICHI KOHIROGAWA.
